FATTY MATERIAL STABILIZED AGAINST
OXIDATION AND STABILIZERS THERE-
FORNoel H. Kuhrt, Rochester, N. Y., assignor to East-
man Kodak Company, Rochester, N. Y., a cor-
poration of New JerseyNo Drawing. Application January 11, 1952,
Serial No. 266,106

10 Claims. (Cl. 99—163)

1

This invention relates to stabilized fatty compositions and to stabilizers for fatty material normally subject to oxidation.

Fatty materials, such as solid fats, fatty oils and fatty acids, and particularly the fatty materials having unsaturated components are normally subject to oxidation and resultant oxidative rancidity due, at least in part, to the development of peroxides in such fatty materials. Since the fatty materials such as the animal fats and the vegetable oils, whether unhydrogenated or partially hydrogenated, are widely used as cooking fats, salad oils, shortenings and the like, the fatty materials must be stabilized against objectionable oxidation.

It is accordingly an object of this invention to provide new fatty compositions characterized by improved stability against deleterious peroxide formation and resultant oxidative rancidity.

It is a further object of the invention to provide new stabilizer compositions suitable for incorporation in fatty materials normally subject to oxidation and effective to stabilize such fatty materials against objectionable oxidation.

It is also an object of the invention to provide new stabilized compositions consisting predominantly of fatty triglycerides.

Another object of the invention is to stabilize edible fatty materials against development of objectionable oxidative rancidity under normal storage conditions.

Another object of the invention is to provide improved animal fat or vegetable oil compositions, including both unhydrogenated and partially hydrogenated compositions.

Another object of the invention is to stabilize fatty material against oxidation without impairment of the desirable physical and chemical properties of such fatty material.

Other objects will be apparent from the description and claims which follow.

These and other objects are attained in accordance with this invention by incorporating in a fatty material normally subject to oxidation, a solution of glycine and phosphoric acid in a hydroxy polyoxyalkylene ester of a fat-forming fatty acid.

The invention is applicable for stabilizing any of the well-known fatty materials normally sub-

2

ject to oxidation, including both solid fats and fatty oils, and particularly the fatty materials consisting predominantly of fatty triglycerides or fat-forming fatty acids containing unsaturated components and hence subject to oxidation. The fatty triglycerides include animal fats such as lard, tallow and the like, and vegetable oils such as cottonseed oil, soybean oil, peanut oil, coconut oil, corn oil and the like, whether unhydrogenated or partially hydrogenated, and including the animal and vegetable shortenings. The fatty acids include any of the pure or mixed unsaturated fatty acids as typified by oleic acid and linoleic acid.

15 The stabilizer composition embodying this invention comprises a solution of glycine and phosphoric acid in a hydroxy polyalkylene oxide ester of a fat-forming fatty acid. Any of the well-known hydroxy polyoxyalkylene esters of fat-forming fatty acids can be employed in practicing this invention provided such esters have a melting point not substantially higher than 100° C., and those esters having a melting point below 90° C. are preferred. The hydroxy polyoxyalkylene esters employed in practicing the invention are obtained in accordance with known practice by condensing a fat-forming fatty acid with from 5 to 60 molar proportions of an alkylene oxide or by reacting a fatty acid with an alkylene oxide polymer. The polyoxyethylene derivatives are desirably employed in practicing this invention although other oxyalkylene derivatives such as 1,2-propylene oxide or 1,3-propylene oxide derivatives can be employed if desired. The ester can be a hydroxy polyoxyalkylene ester of any of the well-known fat-forming fatty acids, with those fatty acids having at least 12 carbon atoms in the fatty acid molecule being preferred, as typified by lauric acid, stearic acid, oleic acid, palmitic acid and the like. Good results are obtained over a wide range of esters as, for example, with hydroxy-8-oxyethylene monostearate and hydroxy-40-oxyethylene monostearate, the number in each case referring to the molar proportions of ethylene oxide for each molar proportion of fatty acid.

In preparing the stabilizer composition, glycine and phosphoric acid are dissolved in the polyoxyethylene fatty ester, either with such ester

in liquid form or with the glycine and phosphoric acid in solution in a suitable mutual solvent such as glycerine. The concentration of glycine and phosphoric acid in the ester solution can be varied as desired up to the limit of solubility. The stabilizer composition is then incorporated in the fatty material to be stabilized, with best results being obtained by incorporation at a temperature of 40-95° C. and more desirably at 50-90° C., temperatures above 95° C. being less desirable because of impairment of the effectiveness of stabilization. The glycine and phosphoric acid provide effective stabilization at concentrations of each of from 0.00005% to 0.02% by weight based on the total composition weight. Larger amounts of glycine and phosphoric acid can be employed if desired, with amounts as high as 0.5% or higher of each of such materials being suitable. Best results are obtained with the phosphoric acid present in an amount not greater than twice the weight of glycine, although larger proportions of glycine can be used without adverse effect. The amount of hydroxy polyoxyalkylene fatty acid ester can be varied but is desirably present in an amount not greater than 5% by weight of the total weight of the stabilized fatty composition. In the preferred triglyceride compositions, the fatty triglycerides are present in an amount equal to at least 85% of the total composition weight.

The glycine and phosphoric acid are desirably employed in the form of the free acids. Materials furnishing glycine or phosphoric acid in the fatty composition can be employed, however, and are within the scope of the invention. Thus, for example, the phosphoric acid can be furnished by a salt of phosphoric acid such as sodium phosphate, and the glycine can be added as a crude soy protein hydrolysate within the scope of the invention.

The development of oxidative rancidity is usually evaluated by analysis of the peroxide content of a fatty composition, a peroxide value of 20 millimols of peroxide per kilogram of fatty composition usually being considered the maximum permissible value for commercial use. The stability of fatty compositions is evaluated by the accelerated Active Oxygen Method (AOM) wherein a sample of the composition being evaluated is heated on a steam bath at a temperature of 96° C. with air bubbling through the sample and the time necessary for attaining a peroxide value of 20 is determined by periodic analysis of the peroxide content and considered the measure of stability.

The following specific examples illustrate certain preferred embodiments of the invention, it being understood that such examples are illustrative and are not intended to limit the scope of the invention unless otherwise specifically indicated.

Example 1

A solution of 4% by weight of glycine and 4% by weight of phosphoric acid in glycerol was mixed with hydroxy-40-oxyethylene monostearate in an amount sufficient to give a solution of 0.02% by weight of each of the glycine and phosphoric acid in the monostearate. The resulting solution was stirred into oleic acid in an amount of 1.5% by weight of the glycine-phosphoric acid-monostearate composition based on the weight of oleic acid, at a temperature of approximately 60° C. The stabilized fatty composition obtained thereby was tested for stability under the accelerated AOM test conditions and

it was found that the stability of the oleic acid with respect to the time necessary to reach a peroxide value of 20 had been increased 60% over the untreated control sample.

Example 2

A stabilized lard composition containing 0.0003% by weight of glycine, 0.0003% by weight of phosphoric acid, and 1.5% by weight of hydroxy-40-oxyethylene monostearate was evaluated by the AOM accelerated test. The stabilized composition required 29 hours to reach a peroxide value of 20 as compared to 7 hours for unstabilized lard.

Example 3

A partially hydrogenated cottonseed oil shortening was stabilized by admixing therewith 1.5% by weight of a solution of 0.02% by weight of glycine and 0.02% by weight of phosphoric acid in hydroxy-40-oxyethylene monostearate. The AOM stability of the shortening was increased 40% by such stabilization.

Similar results are obtained with other hydroxy polyalkylene fatty acid esters, with other fatty materials and with varying concentrations of glycine and phosphoric acid, and it will be understood that variations and modifications can be effected within the spirit and scope of the invention as described hereinabove and defined in the appended claims.

I claim:

1. A fatty composition consisting predominantly of fatty material normally subject to oxidation and having incorporated in said fatty material a solution of glycine and phosphoric acid in a hydroxy polyalkylene oxide ester of a fat-forming fatty acid.

2. A normally solid fat having incorporated therein a solution of glycine and phosphoric acid in a hydroxy polyoxyethylene ester of a fat-forming fatty acid.

3. A fatty oil having incorporated therein a solution of glycine and phosphoric acid in a hydroxy polyoxyethylene ester of a fat-forming fatty acid.

4. A fatty composition consisting predominantly of fatty triglycerides and having dispersed therein a minor amount of a solution of glycine and phosphoric acid in a hydroxy polyoxyethylene ester of a fat-forming fatty acid.

5. A fatty triglyceride composition having incorporated therein a solution of glycine and phosphoric acid in a hydroxy polyoxyethylene ester of a fatty acid having at least 12 carbon atoms in the fatty acid molecule, said glycine and said phosphoric acid each being present in an amount of not more than about 0.02% by weight based on the total weight of said composition, said phosphoric acid being present in an amount not greater than twice the weight of said glycine.

6. A fatty composition comprising at least 85% by weight of fatty triglycerides, from 0.00005% to 0.02% by weight of glycine, and from 0.0005% to 0.02% by weight of phosphoric acid, all based on the total composition weight, said glycine and phosphoric acid being present in solution in a hydroxy polyoxyethylene ester of a fatty acid having at least 12 carbon atoms in the fatty acid molecule.

7. A shortening having incorporated therein a solution of glycine and phosphoric acid in a hydroxy polyoxyethylene ester of a fat-forming fatty acid.

8. A stabilizer composition suitable for incorporation in fatty material normally subject to

oxidation, said composition comprising a solution of glycine and phosphoric acid in a hydroxy polyalkylene oxide ester of a fat-forming fatty acid.

9. A stabilizer for fatty material comprising a solution of glycine and phosphoric acid in a hydroxy polyoxyethylene ester of a fatty acid having at least 12 carbon atoms in the fatty acid molecule.

10. A stabilizer for fatty material comprising a solution of glycine and phosphoric acid in a hydroxy polyoxyethylene ester of a fatty acid having at least 12 carbon atoms in the fatty acid

molecule, said phosphoric acid being present in an amount not greater than twice the weight of said glycine.
